Filed Mar. 13, 1962, Ser. No. 179,355
3 Claims. (Cl. 81—125)

The present invention relates to tools generally and in particular to a socket wrench of the screwdriver type.

An object of the present invention is to provide a useful tool adapted to start bolts and the like in hard to reach places, one which has means for retaining a bolt in the tool until the bolt is started in its position in a bolt hole, and one which is highly effective in action.

Another object of the present invention is to provide a hand tool of the screwdriver type which may be employed with long or short bolts, one which serves to free the hand of the user in starting bolts or the like, and one which can be manufactured in quantity at reasonable cost.

A further object of the present invention is to provide a screwdriver type magnetic tool having replaceable sockets so as to accommodate bolt heads of various sizes, the magnetic portion of the tool being operable with any size socket desired.

These and other objects and advantages of the present invention will be fully apparent upon consideration of the following description of the tool of the present invention, the description to be considered in the light of the drawing attached, in which:

FIGURE 1 is a cross-sectional view of the tool of the present invention,

FIGURE 2 is a view partially in section showing the tool in use,

FIGURE 3 is a view taken on the line 3—3 of FIGURE 1,

FIGURE 4 is a view of the portion of the tool showing how a bolt is held in a straight position,

FIGURE 5 is a sectional view of a modified form of the socket portion of the tool,

FIGURE 6 is a view taken on the line 6—6 of FIGURE 5, and

FIGURE 7 is a view similar to FIGURE 5 showing a larger socket in use on the tool of the present invention.

Referring in detail to the drawing, the socket wrench of the present invention comprises an elongated hollow body 10 preferably fabricated of a non-magnetic material. In the form of the invention shown in FIGURES 1 to 4, inclusive, the body 10 has one end flared out to form a socket constituting means on one end of the body 10 adapted to engage the head of a bolt, the flared out end portion being designated by the reference numeral 12 and the bolt being designated by the numeral 14.

A handle 16 is carried on the other end of the body 10 and preferably is fabricated of plastic material or the like.

One end of the handle is formed with a bore 18 of a size to receive therein the adjacent end portion of the body 10 and the other end of the handle 16 is provided with a threaded bore 20 having a diameter less than the diameter of the bore 18. The bores 18 and 20 are disposed in longitudinal alignment with the interior of the body 10 and are connected in communication therewith.

A rod 22 has a threaded portion 24 adjacent one end threadably engaged in the bore 20 of the handle 16. A knurled wheel 26 is mounted upon the free end of the rod 22 adjacent the threaded portion 24 and provides a means for gripping the rod 22 in order to rotate it within the handle 16 to advance or retract the rod 22 with respect to the body 10.

The other end of the rod 22 remote from the knurled

2

wheel 26 carries a magnet 28 of a diameter to slidably fit within the bore 30 of the body 10.

In the form of the invention shown in FIGURES 5 to 7, inclusive, the body 10 is provided on its lower end with an outwardly bent lug element 32 received in a recess 34 provided in the stem portion 36 of a removable socket 38.

In FIGURE 7, a socket 38' is shown of a greater diameter than the socket 38 shown in FIGURES 5 and 6.

10 The stem 36' of the socket 38' fits on the end of the body 10' as in FIGURES 5 and 6.

In use, the magnet 28 is insertable into and withdrawable from the sockets 12, 38, 38' by turning the rod 22 within the handle 16. This permits the tool of the present invention to position a fastening element such as the bolt 14 in position adjacent the hole to receive it and to start the bolt 14 with ease and facility.

15 In FIGURE 4 it will be seen that the bolt 14 might be at a cocked angle previous to seating on the magnet 28 but 20 that the magnet 28 will hold the bolt in a straight position as in FIGURES 1 and 2 after the magnet has contacted the head of the bolt.

The tool of the present invention makes it possible for 25 bolts of all lengths and sizes to be started in inaccessible places where the fingers may not be able to hold the bolt and it also frees the hand of the user which normally would have to hold the bolt while a wrench was applied.

30 Sockets of all sizes may be provided for use with the tool and it is expected that numerous changes and modifications may be made in the invention as will be found practical without departing from the spirit of the invention as set forth in the appended claims.

What is claimed is:

35 1. A socket wrench comprising an elongated hollow body, means on one end of said body adapted to engage the head of a bolt, a handle carried on the other end of said body, said handle having a threaded bore therein disposed in longitudinal alignment with the interior of said body and connected in communication therewith, 40 a rod having the portion adjacent one end exteriorly of said handle and having the other end inwardly of and spaced from said one end of said body, said rod being provided with threads on the portion within said handle threadably engaging the threads of said bore, a magnet 45 carried on the other end of said rod, and handle means on said one end of said rod for the application of rotative force to said rod whereby said magnet is moved toward or away from the bolt head engaging means responsive to execution of rotary movement of said handle in one or 50 the other direction.

2. A socket wrench comprising an elongated hollow body, means embodying a fixed socket on one end of said body, means on one end of said body adapted to engage the head of a bolt, a handle carried on the other 55 end of said body, said handle having a threaded bore therein disposed in longitudinal alignment with the interior of said body and connected in communication therewith, a rod having the portion adjacent one end exteriorly of said handle and having the other end inwardly of and spaced from said one end of said body, said rod being provided with threads on the portion within said handle threadably engaging the threads of said bore, a magnet carried on the other end of said rod, and handle means on said one end of said rod for the application of 60 rotative force to said rod whereby said magnet is moved toward or away from the bolt head engaging means responsive to execution of rotary movement of said handle in one or the other direction.

3. A socket wrench comprising an elongated hollow body, means employing a removable socket on one end of said body, means on one end of said body adapted to engage the head of a bolt, a handle carried on the other

end of said body, said handle having a threaded bore therein disposed in longitudinal alignment with the interior of said body and connected in communication therewith, a rod having the portion adjacent one end exteriorly of said handle and having the other end inwardly of and spaced from said one end of said body, said rod being provided with threads on the portion within said handle threadably engaging the threads of said bore, a magnet carried on the other end of said rod, and handle means on said one end of said rod for the application of rotative force to said rod whereby said magnet is moved toward or away from the bolt head engaging means re-
